UNITED STATES PATENT OFFICE.

JAMES McDONALD AND GEORGE P. HAYNES, OF NEW YORK, N. Y., ASSIGNEES TO TODD SHIPYARDS CORPORATION, OF NEW YORK, N. Y., A CORPORATION OF NEW YORK.

LIQUID-FUEL FURNACE.

Application filed February 6, 1923. Serial No. 617,269.

To all whom it may concern:

Be it known that we, JAMES McDONALD and GEORGE P. HAYNES, both citizens of the United States, and residents of the borough of Manhattan, in the city, county, and State of New York, have invented certain new and useful Liquid-Fuel Furnaces, of which the following is a specification.

This invention relates to liquid fuel furnaces, and our improvements are directed to the control means for regulating the quantity of air admitted to furnace fronts for delivery to the burners thereof.

In the operation of a liquid fuel furnace it is of course necessary to adjust the air inlet means for the admission of a supply of air proportionate to the quantity of liquid fuel supplied to the burner in order that combustion may take place under the most satisfactory conditions.

Hitherto the operator in charge of the furnaces has adjusted the air inlet means, with the result that the degree of skill or experience of the operator determined the extent to which the calorific value of the fuel has been utilized.

Actually, the method of ascertaining the character of the combustion which takes place in a furnace is by analysis of the resultant gases, and it is the purpose of our invention to establish a limit beyond which the air inlet means cannot be opened, that limit representing the fully open condition of the air inlet means to supply a pressure of air which has been determined to be proportionate to a given quantity of liquid fuel for the most efficient combustion.

Other features and advantages of our invention will hereinafter appear.

In the drawings:

Figure 1 is a partial front elevation of a boiler having a number of furnaces.

Fig. 2 is a face view, on a larger scale, showing the outer plate of a furnace front.

Fig. 3 is a section on the line 3-3 of Fig. 2.

Fig. 4 is a section on the line 4-4 of Fig. 3.

Fig. 5 is an enlarged detail of the setting means for the air admission opening, and

Fig. 6 is a front detail of the cone which co-acts with the Venturi tube to regulate the air supply to the burner.

The representation in the drawings is that of Todd type burners and furnace fronts, three furnaces equipped therewith being shown as serving a Scotch marine boiler 1. The general organism of the furnace fronts includes the spaced, forward and back plates 2 and 3, the plate 2 having the annular rib 4, upon which is seated, in fixed relation, a circular wall 5 that extends from the plate 3 and is provided with ports 6, for the admission of air that flows thereto from the boiler casing, in the manner known in the art as the Howden draft. The wall 5 is encircled by a revoluble ring 7, here shown as composed of three segments, united by bolts as at 8, each segment provided with a set of external gear teeth 9, for a purpose to be described hereinafter. The ring 7 is also provided with ports 10 which are adapted, in the rotation of the ring, to co-act with ports 6 to regulate the quantity of air flowing into the furnace front.

Fig. 3, which shows on a relatively large scale the structure of the furnace front, includes the Venturi tube 11, burner tube 12, and the cone 13 which is movable longitudinally thereof to regulate the air passage through the Venturi tube, these elements forming no part of the present improvements.

Meshed with the gear teeth of a segment of the ring 7 is a pinion 14, carried by a shaft 15 that is journaled in a plate 16, secured to forward plate 2, the shaft 15 having a lever 17 by which it and pinion 14 may be rotated, to thereby rotate ring 7, for opening and closing ports 6, also for varying the extent to which said ports are opened.

It is however our purpose to limit the extent to which the ring 7 can be rotated, setting the limit at a point where the open condition of the ports 6 is such as to admit the proper determined pressure of air to effect the most efficient combustion of the fuel. When this setting has been found, a serrated block 18 is engaged by its teeth with a serrated segment 19 on plate 16, being secured thereto as by bolt 20, said block 18 then serving as an adjustable stop in the path of lever 17, to arrest its further movement in the port opening operation. A fixed stop 21 upon plate 16 may serve to limit the port closing operation of lever 17. The lever 17 is shown as provided with the inclined wear

faces 22 to co-operate respectively with the stops 18 and 21.

With the stop 18 set and secured in a predetermined position, as for instance indicated in Fig. 5, the lever 17 can be swung around into contact therewith, to thereby rotate the ring 7 into a position where its ports 10 will co-operate with the ports 6 to provide the desired clearances for air admission. 10 Hence the operator is required to merely swing lever 17 around to the limit of its movement to enable a proportionate pressure of air, commensurate with a desired quantity of liquid fuel, for the production of a predetermined, proportionate mixture of liquid fuel and air.

The ring 7 is cast in several sections for convenience, also because, when one set of teeth 9 becomes worn, the ring may be shifted to bring another set of teeth into co-operation with pinion 14.

A structural feature of improvement disclosed in this application consists of the angularly disposed, annular flange 23, secured to the inner surface of back plate 3, and serving to confine certain heat insulation material 24, which protects the riveted junction between the furnace and boiler against the distorting effects of the furnace heat.

While our improvements are primarily directed to means for providing a variably settable stop for limiting the air admission opening means in a forced draft furnace, we also provide means whereby the furnace can be conveniently adapted for use under induced draft conditions.

This conversion is effected by rotating the ring 7 to close the ports 6 and by providing in the plate 2 an ample opening 25, which is normally closed by the upper and lower doors 26, 27, these doors being hinged respectively at 28 and 29, so that the door 26 opens by swinging downwardly, and the door 27 opens by being swung upwardly.

Pivotal handles 30, 30, mounted in the doors 26, 27, each have an inner latch portion 31 to engage the inner surface of wall 2 for locking the doors when shut.

The upper door, when opened, will stay open by gravity. But the lower door, which opens upwardly, is held open by means of a pivotal latch 32, mounted on the plate 2, and adapted to be turned to engage the rear edge of the door when the latter is open.

Variations within the spirit and scope of our invention are equally comprehended by the foregoing disclosure.

We claim:

1. In a furnace front having fixed air intake ports, in combination, a rotatable ring having ports to co-operate with said intake ports to regulate their effective area, means for rotating said ring, and stop means ad-

justable to a predetermined position to limit the extent to which the ring can be rotated. 85

2. In a furnace front having forward and back plates in spaced relation, in combination, an enclosing annular wall having air intake ports, a ring revolvably mounted on said annular wall and having ports to co-operate with said intake ports, a pinion mounted in the forward plate and adapted to mesh with the gear teeth, a lever to operate said pinion, and a stop adjustable to a set position on the forward plate in the path of the lever, to limit the movement of said lever when swung in the direction for opening the air intake ports. 75

3. In a furnace front having peripheral air intake means, a revolvble ring having 80 openings to co-act with said intake means, said ring provided with gear teeth, a pinion mounted on the furnace front to engage the gear teeth, a lever to operate the pinion, a serrated segment upon the furnace, and a 85 stop settable upon said segment in a predetermined position in the path of the lever to limit the degree of the lever ring shifting movement.

4. The combination with a furnace front 90 having peripheral air intake means of an air control ring, composed of detachably engaged sections, revolvably applied thereto, each section having gear teeth, and means adapted to co-act with the teeth of one section to actuate the ring. 95

5. The combination, with a furnace front having peripheral air intake means, of an air control ring revolvably applied thereto, said ring consisting of detachably engaged sections for adjustment, each section having gear teeth, and means adapted to co-act with the teeth of any one of the sections to actuate the ring. 100

6. The combination, in a furnace having liquid fuel supply means and air supply means, the latter comprising peripheral air intakes provided in the furnace front, and a revolvble ring, having ports, to co-act with the intakes, of mechanical means for limiting the quantity of air admitted to the furnace so that the air supplied is proportionate to the liquid fuel, said mechanical means consisting of a stop that is adjustable to a fixed position on the furnace front and means 110 for turning the ring to open the intake means, the stop limiting such turning movement at a predetermined point for which it is set to achieve proportionality of the air supply relatively to the liquid fuel supply. 115

Signed at the borough of Manhattan, in the city, county and State of New York, this 25th day of January, A. D., 1923.

JAMES McDONALD.
GEORGE P. HAYNES.
